W. H. H. WELTON

METAL RAILROAD TIE AND RAIL FASTENER

Filed Dec. 5, 1922

William H. H. Welton

INVENTOR.

UNITED STATES PATENT OFFICE.

WILLIAM H. H. WELTON, OF DALLAS, TEXAS.

METAL RAILROAD TIE AND RAIL FASTENER.

Application filed December 5, 1922. Serial No. 605,120.

To all whom it may concern:

Be it known that I, WILLIAM H. H. WELTON, a citizen of the United States, residing at the city and county of Dallas and State of Texas, have invented certain new and useful Improvements in Metal Railroad Ties and Rail Fasteners in Connection with Railroad Construction, and may be said to be an improvement on my former Patent No.

10 1,388,226.

I do declare the following to be a full, clear and exact description of the invention such as will enable others skilled in the art to which it appertains to make and use the same, reference being had to the accompanying drawings and to the characters of reference marked thereon which form a part of this specification. The object of this invention is to provide a tie and fasteners of any desired width for rails in railroad construction which can be quickly laid and rails can be quickly changed, that makes a rail bearing as wide as the tie and reinforces the tie under the rails, and having no parts which will readily loosen when in use.

In railroad construction the wider the tie used, the less number it takes per mile, and a greater rail and ground bearing is secured by using wide ties of this construction.

Briefly the invention comprises a tie of trough or channel shape preferably of suitable non-corrosive metal; a mixture of iron or steel with other metals, square inside or outside and adapted to receive a pair of fasteners slidable longitudinally of the tie, and having means to engage opposite sides of the rail. Wedge shaped devices are provided for anchoring the fasteners within the tie, thereby preventing movement of the rail upon the tie. Ties may be as wide as can be used.

In the drawings—

Figure 1 is a perspective view partly broken away showing the parts in operative relation, showing the rails in position.

Figure 2 is an end view and the construction of Figure 1.

Figure 3 is a view of a fastener before being placed in position in the tie.

Figure 4 is a brace for the side of the rail to be used on curves and at switches as shown in Fig. 1—123, to be riveted or bolted on the top of the fastener and fits the base and the web of the rail, and acts jointly as a clip where used. Each tie has shallow recesses cut in the top of each side

thereof, and adjacent each end, said recesses being of a length equal to the width of the rail bases and adapted to receive the rail bases, which prevents the rails from spreading. Slots are provided in the tie near the recesses Fig. 1, 27 and 28 a long slot 27, one side the tie with a short slot opposite on the other side the tie. On the other side the rail, the slots are reversed. Two fasteners Fig. 3 are provided for each rail, these fasteners being identical in construction and adapted when in operative position to be slid longitudinally within the tie, and to have a reasonably snug fit and to reinforce the tie under the rails and support the rails the full width of the tie. In positioning the fasteners they sit side by side in the tie, under the rails, one with the long slot on one side of the rail, the other reversed with the long slot on the other side of the rail. Each fastener comprises a trough shaped piece of metal, common channel iron with the closed side up, half as wide as the inside of the tie, with side as deep as the tie is inside under the rails below the notches and long and heavy enough to properly reinforce the tie under the rails and make a rail bearing as wide as the tie with one or more raised clips, stamped out of the top of the fasteners Fig. 3—23 in such a place that when in operative position the rail will be on the center of the fastener.

The side of the fastener next to the side of tie is provided with a long slot and a short slot. When in position the long slot in the fastener is opposite the long slot in the tie and short slot opposite the short slot in the tie. The other sides of the fastener are provided with slots as long as half the length of the long and the short slots, otherwise, longer than short slots and shorter than the long slots, slots being opposite slots in the other side of the fastener so when in position they would be the same distance from the base of the rails and opposite the slots in the tie, said slots being adapted to receive tapering locking keys or wedges which pass through the long slots and the short slots in the tie and through the slots in the fasteners. I would have slots in the tie and fasteners large enough to admit a tapering key or wedge strong enough to hold the fasteners securely in position in the tie against the base of the rails. I would make all parts of suitable non-corrosive metal, thus increasing the durability of the tie, as

soon as such metal becomes available in cost.

In order to provide means for bracing the rails on curves and around switches a brace is provided as shown Fig. 4, to be riveted or bolted on top of the fastener Fig. 1—123, and made to fit the base and web of the rails.

At switches I would use special ties and fasteners. I would use fasteners long enough to support both rails when too close together to use one fastener at each rail with clips stamped on them in such a position as to engage both rails or I would bolt a clip on the fasteners to engage the second rail until the rails are far enough apart to use regular fasteners under each rail, all ties to be as wide as can be safely used.

At joints I would use fish plates that fit the under side of the crown, the web and the top of the base of the rails, with a base narrower than the rail bases and come to a thin edge so as not to interfere with the clips on the rail fasteners. When block signals are in use insulation as described in my Patent No. 1,388,226 or any other system of insulation may be used. When using insulation the keys or wedges may need to be narrower than the regular keys or wedges.

From the foregoing it will be seen that I have provided simple and efficient means for supporting and anchoring rails in railroad construction and for insulating the same when required. The tapering keys or wedges when driven through the various slots of gradually decreasing lengths are firmly anchored and may be securely retained by bending down the small end with a hammer. I would also hammer the point of the clips down securely to the rail base. Thus there is nothing which can work loose, and the ties will be secured to the rail permanently, renewal being required only when the ties have completely worn or rusted out, and if necessary to change rails it can be easily and quickly done.

I claim:

1. In combination a trough shaped tie a pair of members which support the rails and reinforce the tie under the rails, slideable within the tie, said members being each of a width equal to one-half the width of the tie inside, each member being provided with two parallel sides and joined by a web and provided with clips for engagement with the flanges of a railroad rail, said members being identical in construction, and means for securing said members to the tie and clamping them against the flanges of the rail.

2. In combination, a trough shaped tie a pair of members which support the rails, and reinforce the tie under the rails, slideable within the tie, said members being each of a width equal to one-half the width of the tie inside, each member being provided with two parallel sides as wide as the tie is deep

inside under the rails and joined by a web and provided with clips for engagement with the flanges of a railroad rail, and means for securing said members to the tie and clamping them against the flanges of the rail, one side of each member being provided with two slots of unequal length, the other side being provided with two slots of equal length, cooperative slots in the sides of the tie and means cooperating with said slots for securing said members to said tie and clamping the clips against the flanges of a railroad rail.

3. In combination, a trough shaped tie a pair of members identical in construction which support the rails and reinforce the tie under the rails, slideable within the tie, said members being each of a width equal to one-half the width of the tie inside, each member being provided with two parallel sides and joined by a web and provided with clips for engagement with the flanges of a railroad rail, one side of each member being provided with two slots of unequal length, the other side with two slots of equal length, cooperating slots in the sides of the tie, means cooperating with said slots for securing said members to said ties and clamping the clips against the flanges of a railroad rail, a brace being riveted or bolted on one of the rail fasteners for engagement with the web and base of a railroad rail acting as a clip where used.

4. In combination a trough shaped tie, notches in the upper edges of the sides of the tie near each end thereof, railroad rails seated in said notches, a pair of members slideable within said tie near each end thereof, said members each being of a width equal to one-half the inside of the tie, each member comprising two parallel sides as deep as the tie inside under the rails, joined by a web, said members being each provided with clips for engaging the flanges of the railroad rails, said clip being riveted or bolted on the fasteners, and means for securing said members to said tie and forcing said clips against said flanges.

5. In combination a trough shaped tie with notches in the upper edges of the sides of the tie near each end thereof, railroad rails seated in said notches, a pair of members identical in construction, slideable within said tie near each end thereof, said members being each of a width equal to one-half the width of the inside of the tie, each member comprising two parallel sides as deep as the tie inside under the rails, and joined by a web, and provided with clips for engagement with the flanges of a railroad rail, said members acting as a bridge between the bottom of the tie, and the bottom of the rail, and reinforcing the tie under the rails, one side of said members being supplied with two slots of unequal length, the other with

two slots of equal length, cooperating slots in the side of the tie, means cooperating with the said slots for securing said members to said tie and forcing said slips against said flanges.

6. In combination a trough shaped wide tie with notches in the top edges thereof, railroad rails seated in said notches, a pair of members identical in construction, slideable within said tie near each end thereof, said members each being of a width equal to one-half the width of the inside of the tie, each member comprising two parallel sides as deep as the tie inside under the rails, joined by a web, said members being provided with clips for engaging the flanges of the said railroad rails, one side of each member being provided with two slots of unequal length, the other side with two slots of equal length, corresponding slots in the sides of the tie means cooperating with said slots for securing said members to said ties and forcing said clips against said flanges. ¹⁵ ²⁰

In testimony whereof I affix my signature.

WM. H. H. WELTON.
